UNITED STATES PATENT OFFICE.

JAMES W. VAN METER, OF SAN FRANCISCO, CALIFORNIA.

ORE STAMP MILL.

1,405,467.

Specification of Letters Patent. Patented Feb. 7, 1922.

Application filed February 23, 1921. Serial No. 447,198.

To all whom it may concern:

Be it known that I, JAMES W. VAN METER, a citizen of the United States of America, residing at 2977 Clay Street, San Francisco, 5 in the county of San Francisco and State of California, have invented certain new and useful Improvements in Ore Stamp Mills, of which the following is a specification.

The present invention is an improved 10 stamp mill and relates to that type of ore crushing devices in which ore and the like are crushed by a violent blow or impact.

Heretofore this operation has been carried on by dropping heavy stamps within a 15 mortar repeatedly until the material is reduced to the required fineness. I prefer the reverse operation of stamping ores and have found it more advantageous to lift or drive the mortar against a fixed stamp.

20 Attention is directed to United States Patents Numbers 1,353,096 and 1,353,097 issued to me on Sept. 14th, 1920.

One object of my invention is to provide a mill of the type described which will 25 reduce ore to a given fineness with the minimum number of blows and which will scavenge the mortar of finely ground ore at once instead of permitting same to become impacted around particles not yet reduced.

30 Another object attained by my invention is that it is possible to operate the mill without any ore or material in the mortar without danger of breakage.

In the embodiment of my invention here 35 shown the lower extremity of the mortar is provided with a cylinder and piston and an expansive fuel charge is utilized to drive the cylinder and mortar (integrally formed) upward against a fixed stamp.

40 I employ two opposed cylinders in my mill, the one just described for the expansive fuel and one as a counter balance or cushion chamber for the heavy mortar.

I utilize air pressure to give the necessary 45 degree of compression of the fuel charge in the working chamber and after the charge is expanded the force of the blow is augmented by admitting compressed air to the second chamber and this air is also used to 50 cushion the weight of the mortar on its return or downward stroke.

The lower extremity of the secondary or

cushion chamber is used to retard or stop the upward movement of the mortar at a predetermined fixed point to prevent actual 55 impact of the mortar against the fixed stamp and thus avoid breakage.

While the stamp here shown is of the internal combustion engine type I do not limit myself to this type and it is obvious that 60 steam, compressed air or other suitable agency may be employed to drive the mortar.

In this specification and the annexed drawings, the invention is illustrated in the form 65 considered to be the best, but it is to be understood that the invention is not limited to such form, because it may be embodied in other forms and it is also to be understood that in and by the claims following the description it is desired to cover the invention 70 in whatever form it may be embodied.

In the accompanying 6 sheets of drawings:

Fig. 1 is a front elevation of my improved 75 stamp mill.

Fig. 2 is a side elevation of my improved stamp mill partly in section, showing the 70 mortar up in crushing position.

Fig. 3 is a view similar to Fig. 2 but showing the mortar in the down position, (taken 80 on line III—III of Fig. 7).

Fig. 4 is a fragmentary section view of the explosion cylinder within the mortar showing the firing means.

Fig. 5 is a view similar to Fig. 4 showing 85 air passages and water cooling circulation, and the section is on a different plane.

Fig. 6 is an arcuate section taken on the line VI—VI of Fig. 8 showing the various 90 valves for controlling compressed air.

Fig. 7 is a top plan view of Fig. 1.

Fig. 8 is a section taken on the line VIII—VIII of Fig. 2.

Referring to the drawings, Figs. 1 and 2, the numeral 1 designates a stand or base to 95 which are secured, as by bolts 2, upright arms or guides 3, 4 and 6. A mortar 7 is provided with three pairs of lugs 8 distributed circumferentially around the outside thereof which said lugs are bored to 100 form a sliding fit over rods 5 slidable in guides 3, 4 and 6 and make the mortar 7 reciprocable vertically thereon.

The upper extremities of the rods 5 are

reduced as shown at 9, Fig. 3, and against the shoulder 11 formed thereby a sleeve 12 abuts.

An anvil or fixed stamp 13 is secured to said rods 5 by nuts 14 and washers 16. The vertical position of this anvil may be determined by the use of various lengths of sleeves 12.

The lower extremities of rods 5 are also reduced as shown at 17, Fig. 3, and secured against the shoulders so formed is a base plate 18 held in position by nuts 19.

The base plate 18 is provided with an annular flange 21 which rests on a metal plate 20 which in turn rests on a rubber cushion 22 in a sump in the stand.

It will be seen that the stamp or anvil 13 is rigidly secured to the base plate 18 by rods 5 and that these rods are held in vertical alinement by the arms 3, 4 and 6.

In Fig. 3 I show a central section of my device, the anvil or fixed stamp 13 is provided with a bore 23 which is flared at the top to facilitate the entry therethrough of ore 24 to be crushed which drops into the mortar 7.

The mortar 7 is provided with an annular recess 26 which is of smaller area at the top than at the bottom, for wedge engagement with a composite liner composed of four vertically tapered segments (but two of which are here shown at 27 and 27^a). This segmental arrangement facilitates the assembly of the parts to form a wedge or interlocking engagement adapted to withstand repeated blows.

A tapered die 28 is secured within the composite liner by oppositely tapered wooden wedges 29.

The mortar 7 is chambered as shown at 31 above the mortar box and this chamber is deeper on one side than on the other as indicated by the dotted line 32. This chamber is drained by an orifice shown at 33, Fig. 5.

On the ledge formed between the chamber 31 and the mortar box and liner 27 rest an annular ore screen 34. This screen is held in place by a funnel shaped deflector 36 which acts as a splash to deflect the finely ground wet particles against the ore screen at a suitable angle.

As a precaution against water or ground ore fouling the rods 5, I provide an inverted funnel or flared ring 37 which rests against the deflector 36.

Referring now to Fig. 2, the mortar 7 is bored from the bottom to form a cylinder 38 and a reduced bore constituting a cylinder 39 coaxial therewith extends farther into the mortar.

Reciprocable in these bores is a piston 41 which acts within the cylinder 39. This piston has a shoulder 42 which serves as a piston ton in the bore 38.

The bore or cylinder 38 is closed by a cylinder head 43 suitably secured to the casting of the mortar and arranged to reciprocate therewith over the piston 41 as indicated at 44.

The piston 41 is secured to the base plate 18 by a bolt 46 the head of which is engaged in the boss 21 on the under side of said plate. The bolt extends through a bore in the base plate 18 and through the floor 47 of the hollow piston 41 in which position it is secured by wedge pins 48 and 49 which are inserted through the slots in the lower end of piston 41, and in the upper end of bolt 46, as seen in Figures 2 and 3, but not further described.

A rubber ring or cushion 51 is provided in an annular recess in the under side of piston 42 to prevent direct contact of said piston with the cylinder head 43.

The cylinder 39 is water jacketed for circulation as shown at 52.

At 58, I show an air compartment surrounding the cylinder 39 which communicates with the larger cylinder 38 through ports 59.

The air compartment 58 communicates through a vertical passage 61 in the mortar casting with an air reservoir or chamber 63.

A piston 62 is secured at one end to the base 1 of the mill and at the other end slidably closes the passage 61.

This piston 62 is hollow and furnishes communication between the air compartment 58 and an air chamber 63 being connected thereto by a pipe 64 (Fig. 2).

In Fig. 5, at 66, I show a valve opening outward from the air compartment 58. A removable valve seat is shown at 67. Into this is threaded a plug 68 which has a central bore for a guide for the valve stem and the threads serve to regulate the strength of an expansion spring 69 pressing against the valve 66.

A port 71 allows the air to escape when the valve 66 is open.

For a purpose to be later described communication is made between the cylinder 38 and the air compartment 58 by spring pressed valves 72 and 73 controlling respectively air passages 74 and 76.

Water is supplied to the water jacket 52 through a flexible conduit 77 and finds its way through port 78, passage 79 and pipe 81 to a port 82 communicating with a sump 83 in the mortar box of the mortar.

In Fig. 4, I show a spark plug at 84 in a passage 86 communicating with the cylinder 39 at the top thereof.

Before describing the details of construction further it will be well at this point to describe in a general way the operation of the mill so far described.

Water is fed to the mortar box through the flexible conduit 77, and serves as a circulat-

ing cooling agent for cylinder 39 and the warm water assists materially in the crushing of the ore particles.

The ore or material to be crushed is admitted through the bore 23 of the stationary anvil 13 and gravitates to the mortar box in the mortar 7.

When the mortar is driven upwardly violently the ore is crushed between the mortar and the fixed anvil, and the impact causes a splash of the water and the finely ground ore. This splash is upward in the space around the anvil.

When this splash encounters the deflector 36, which surrounds the anvil 7, the pulp is projected against the screen 34 at substantially a right angle thereto.

As the pulp leaves the screen on the outer wall it gravitates to the bottom of the rounding chamber 31 from which it is taken from the mill through passage 33, Fig. 5.

Fig. 6 is an arcuate section on the line VI—VI of Fig. 8 and the plane is flattened out to illustrate a series of parallel piston valves controlled or operated by the impact of the mortar. The numeral 88 indicates an inlet valve admitting explosive mixture to the explosion chamber or cylinder 39 through ports 89 and 91. The port 89 connects with flexible conduit 87, Fig. 1.

The valve 88 is of the piston type and is hollow. It also carries piston rings on its exterior surface to insure a sliding fit within a sleeve 102 which is also provided with packing rings 103. A renewable liner surrounds the parts so far described and a rubber cushion 107 is used at the top to cushion the impact of the piston valve.

The liner, cushion and piston valve are kept in place by a screw threaded cylinder head 104.

To reciprocate the mortar the air chamber 63 is charged with compressed air until the poppet valve 66 opens.

An expansive mixture under pressure is admitted through a flexible tube 87 (Fig. 1) and passes through valve 88 which valve, when in the position shown in Fig. 6, connects passages 89 and 91.

The mortar will start to rise as soon as sufficient pressure of air is exerted to counterbalance the weight of the mortar plus the vacuum created in cylinder 38 by piston 42.

Slidable in a bore 92, Fig. 6, is a valve 93 provided with a circumferential groove 94. The stem 96 of this valve slides in a plug 97 screw threaded into bore 92. This stem is provided with a passage 98 which conducts air from groove 94 to the atmosphere.

A rod 99 is secured at one end (shown at 100, Fig. 1) to the base 1 of the mill and the upper threaded end is provided with an adjustable cap 101 against which the valve stem 96 abuts when the mortar is down.

It will be seen that, by reason of this con-

struction, when the mortar 7 is raised the valve 94 will remain stationary by reason of air pressure above in cylinder 92 and as the mortar 7 rises the valve 93 slides down in the bore 92. The adjustable cap 101 is set in a position allowing the air to pass from valve chamber 92 into the upper end of chamber containing valve 88.

A by-pass 108 connects the chamber 92 with the upper end of cylinder containing valve 88. At 109 I show one end of a passage connecting the cylinder 92 with the air compartment 58. At 111 I show a by-pass for leakage of compressed air escaping from the valve chamber. Numeral 112 indicates a leakage groove and it communicates with the inside of the hollow valve by port 113. An outlet port for said hollow valve is shown at 114.

At 116 I show a piston valve, the stem 117 of which slides through a plug 118 threaded into a valve chamber 119.

A spring 121 normally supports the valve in the position shown in Fig. 6 but if air pressure is applied within cylinder 119 the spring 121 yields and the descending valve stem closes an electrical circuit with a metal clip 122 which is suitably insulated from the mortar.

A by-pass 123 leads from the cylinder containing valve 88 to the cylinder 119 to actuate the valve 114 and close the circuit.

At 124 I show an exhaust valve similar in construction to the intake valve 88. 126 indicates an exhaust cylinder. A hollow piston 127 removes exhaust gases as the parts reciprocate.

The exhaust cylinder 126 connects with the explosion chamber 39 by means of ports 128 and 129. A leakage groove 131 feeds 105 into a port 132 leading to the interior of the hollow exhaust valve, an outlet for which is provided at 133.

At 134 I show a valve chamber in which reciprocates a piston valve 136. The stem 137 of which is guided by a plug 138, threaded into the chamber 134. The piston valve 136 is formed with three circumferential grooves 137, 138 and 139. The upper and lower grooves (137 and 139) are connected with the atmosphere by a center bore 141 in the valve, while the central groove (138) is connected with the chamber 134 by a bore indicated in dotted lines at 142.

At 143 I show a movable weight slidable 120 in a chamber 144. This chamber has a bleeder opening 146 to allow displacement of air as the weight is shot upward by impact of the mortar 7. The weight is kept in the chamber 144 by a plug 147.

A counter bore 148 connects chamber 144 with valve chamber 134 and serves as a race-way for balls 149 which are moved forward and back in said recess by inclined portions 151 and 152 respectively of the weight 143 130

and the valve 136 for purposes hereinafter described.

The counter bore 148 is closed by a plug 153.

5 A stationary upstanding rod 154 is secured to the base 1 as shown in Fig. 1 and the upper end is threaded and an adjustable cap 156 threaded thereon to engage the stem 137 of valve 136.

10 A by-pass 157 connects the upper end of valve chamber 134 with the air compartment 58.

A passage 158 connects the upper end of the cylinder containing the exhaust valve 124 with the central portion of chamber 134.

15 The operation of my mill is as follows:

The air container 63 is charged with compressed air until poppet valve 66 opens. An explosive mixture under pressure is now admitted through flexible conduit 87. This mixture passes through valve 88 (ports 89, 91). The mortar will begin to ascend as soon as enough pressure is applied to counterbalance the weight of the mortar plus the 25 vacuum created by piston 42. As the mortar rises the valve 93 lowers. The air passes from chamber 92 into the upper portion of intake valve (88) chamber, just before the rising mortar uncovers ports 59 communicating with the air compartment 58.

30 The moment air enters the upper end of chamber 88 from chamber 92 the valve 88 is moved to its lower position closing ports 89, 91 thus cutting off the supply of explosive mixture to explosion chamber 39. At the same moment the air, which is in the upper part of valve chamber 88, will pass out through by-pass 123 forcing piston 114 down and closing the electrical circuit with spark 40 plug 84 thereon, firing the charge in explosion chamber 39.

45 The mortar (now on its upward stroke) uncovers ports 59 in chamber 38 and the compressed air from the container 63 rushes in through piston 62, compartment 58, thus augmenting the force of explosion in raising the mortar.

50 The impact of the upward blow causes the weight 143 (Fig. 6) to raise (being loosely slidably in chamber 144).

Air pressure in the upper part of chamber 134 will now force the piston 136 down and the oblique portion 152 of said piston displaces the balls 149 in the direction of weight 55 143 (now up) locking same.

55 As the valve 136 is driven down air from cylinder 134 passes through port 142 and groove 138 which now coincides with the opening of by-pass 158. The compressed air 60 now enters the top of the chamber containing exhaust valve 124, and forces said valve down throwing port 129 in connection with exhaust chamber 126, at which point the mortar will start to descend.

65 As the mortar descends the air in the upper portion of chamber 36 will be forced back into the container 63. Any excess air that may be drawn in by creating the vacuum from leakage will be blown out through valve 66.

70 The descending mortar now brings the stem 137 of valve 136 in contact with cap 156 on support rod 154 raising said valve in relation to its chamber allowing the air to exhaust from the upper portion of cylinder of valve 124 by way of groove 139 and by-pass 141.

75 The groove 138 will rise to coincide with the port of by-pass 150 whence it passes through conduit, indicated by dotted lines 80 at 155, to the lower portion of the chamber containing exhaust valve 124, driving said valve upward and shutting off communication from explosive chamber 39 to exhaust 126. The air at the same time passes out 85 from the lower portion of chamber 124 through by-pass 133 into the lower portion of valve 88 through port 106. The valve 88 now rises admitting explosive mixture to the explosion chamber 39, air being displaced 90 above piston 88 through by-pass 108, and through the center of valve stem 96.

95 The operation is now repeated.

When the material to be crushed within the mortar box is exhausted the cylinder head 43 encounters the rubber cushion 51 in piston 42. An air cushion is formed in this chamber which retards the upward stroke and the rubber ring or cushion 51 is an auxiliary means for preventing direct 100 contact between mortar and anvil.

One distinct advantage in my mill is the application of a vacuum to retard the rising mortar. By this means I am able to use a comparatively light construction and obtain 105 results, such as better compression of the fuel charge, which would ordinarily require the use of a heavier mortar.

It will be noted that I can vary the amount of vacuum used by varying the strength of 110 the spring controlling the valves on the vacuum line.

It will also be noted that my mill is so constructed that, should the explosive fuel fail in operation, the cycles of operation 115 will be carried on by compressed air.

I claim:

1. A crushing apparatus, comprising, in combination, a fixed anvil, a reciprocating mortar adapted to be driven upward toward 120 said anvil, operating means for said mortar including a rising and falling valve, a weight slidably in said mortar member, and adapted to be moved by the impact thereof, and means operated by the movement of 125 said weight adapted to actuate a valve controlling said mortar.

2. A crushing apparatus, comprising, in

combination, a fixed anvil, a reciprocating mortar adapted to be driven upward toward said anvil, said mortar having a box of greater area at the bottom than at the top, 5 and having in said box an upward tapered die, upward tapered mortar lining segments surrounding said die, and downward tapered wedges between said members.

3. An ore stamp mill comprising in combination a stand, guides on said stand, rods 10 slidable on said guides, a fixed anvil secured to the upper ends of said rods, a base plate secured to the lower ends of said rods, a mortar slidably mounted on said rods between 15 said anvil and said base plate, a piston fixed to said base plate and slidable in a chamber in said mortar, and means for causing an expansive mixture to repeatedly raise said mortar on said piston for the purpose of crushing material in said mortar against said anvil.

4. An ore stamp mill comprising a stand, guides on said stand, rods slidable on said guides, a fixed anvil secured to the upper 25 ends of said rods, a base plate secured to the lower ends of said rods, a mortar slidably mounted on said rods between said anvil and said base plate, a piston fixed to said base plate and slidable in a chamber in said 30 mortar, and means for causing an expansive mixture to repeatedly raise said mortar on said piston for the purpose of crushing material in said mortar against said anvil, said mortar having an auxiliary chamber therein, 35 an auxiliary piston engaging said chamber and secured to said base plate, and means for creating a vacuum in said auxiliary chamber as the mortar rises to retard the movement thereof and thereby assist in the compression of the fuel charge.

5. An ore stamp mill comprising a stand, guides on said stand, rods slidable on said guides, a fixed anvil secured to the upper 45 ends of said rods, a base plate secured to the lower ends of said rods, a mortar slidably mounted on said rods between said anvil and said base plate, a piston fixed to said base plate and slidable in a chamber in said mortar, and means for causing an expansive mixture to repeatedly raise said mortar on said 50 piston for the purpose of crushing material in said mortar against said anvil, said mortar having an auxiliary chamber therein, an auxiliary piston engaging said chamber and secured to said base plate, and means for creating a vacuum in said auxiliary chamber as the mortar rises to retard the movement thereof and thereby assist in the compression of the fuel charge, and means for releasing 55 the said vacuum at a predetermined time to augment the force of the said expansive material.

6. An ore stamp mill, comprising a stand, guides on said stand, rods slidable on said

guides, a fixed anvil secured to the upper 65 ends of said rods, a base plate secured to the lower ends of said rods, a mortar slidably mounted on said rods between said anvil and said base plate, a piston fixed to said base plate and slidable in a chamber in said 70 mortar, and means for causing an expansive mixture to repeatedly raise said mortar on said piston for the purpose of crushing material in said mortar against said anvil, said mortar having an auxiliary 75 chamber therein, an auxiliary piston engaging said chamber and secured to said base plate, and means for creating a vacuum in said auxiliary chamber as the mortar rises to retard the movement thereof and thereby 80 assist in the compression of the fuel charge, and means automatically operated by the movement of the mortar for releasing the said vacuum at a predetermined time to augment the force of the said expansive material.

7. An ore stamp mill comprising a stand, guides on said stand, rods slidable on said guides, a fixed anvil secured to the upper 90 ends of said rods, a base plate secured to the lower ends of said rods, a mortar slidably mounted on said rods between said anvil and said base plate, a piston fixed to said base plate and slidable in a chamber in said 95 mortar, and means for causing an expansive mixture to repeatedly raise said mortar on said piston for the purpose of crushing material in said mortar against said anvil, said mortar having an auxiliary chamber therein, an auxiliary piston engaging said chamber 100 and secured to said base plate, and means for creating a vacuum in said auxiliary chamber as the mortar rises to retard the movement thereof and thereby assist in the compression of the fuel charge, and means for 105 releasing the said vacuum at a predetermined time to augment the force of the said expansive material, adjustable means for varying the degree of vacuum created in said chamber.

8. A crushing apparatus, comprising, in combination, a fixed anvil, a reciprocating mortar having a chamber therein, and adapted to be driven upward toward said anvil, means employing an expansive mixture for so driving said mortar upward, a piston valve in said chamber, means for keeping said piston valve normally suspended in said chamber, and a member rigidly secured to a stationary part of the apparatus and positioned to encounter the said piston valve as the mortar descends, and adapted to thereby operate said valve.

9. An ore stamp mill comprising a stand, guides on said stand, rods slidable on said guides, a fixed anvil secured to the upper 115 ends of said rods, a base plate secured to the lower ends of said rods, a mortar slidably

mounted on said rods between said anvil and said base plate, a piston fixed to said base plate and slidable in a chamber in said mortar, and means for causing an expansive mixture to repeatedly raise said mortar on said piston for the purpose of crushing material in said mortar against said anvil, said mortar having an auxiliary chamber therein, an auxiliary piston engaging said chamber and secured to said base plate, and means for creating a vacuum in said auxiliary chamber as the mortar rises to retard the movement thereof and thereby assist in the compression of the fuel charge, and variable means for determining the amount of vacuum so created.

10. In an ore stamp mill, a mortar bed mounted for upward striking movement, means to cause an expansive agent to impart impulsive upward movement to the mortar bed, and cushioning means to progressively retard and to finally arrest the upward striking movement of the mortar bed.

11. In an ore stamp mill, a mortar bed mounted for upward striking movement, means to cause an expansive agent to impart impulsive upward movement to the mortar bed, and air cushioning means to progressively retard and to finally arrest the upward striking movement of the mortar bed.

12. A piston, a mortar bed, means to cause an expansive agent to repeatedly and im-

pulsively raise the mortar bed on the piston, and means to cushion the descent of the mortar bed.

13. A piston, a mortar bed, means to cause an expansive agent to repeatedly and impulsively raise the mortar bed on the piston, and air cushioning means to control the descent of the mortar bed.

14. A piston, a mortar bed, means to cause an expansive agent to impulsively move the mortar bed on the piston, means to create a partial vacuum behind the mortar bed as the latter impulsively moves and to thereby progressively retard the impulsive stroke thereof, means to break the partial vacuum at an instant during the impulsive stroke and to supply a compressed air cushion to control the reverse stroke of the mortar bed.

15. A piston, a mortar bed, means to cause an expansive agent to impulsively move the mortar bed on the piston, means to create a partial vacuum as the mortar bed impulsively moves and to thereby progressively retard the impulsive stroke thereof, and means to break the partial vacuum at an instant during the impulsive stroke and to hence permit final acceleration of such impulsive stroke.

In testimony whereof I affix my signature.

JAMES W. VAN METER.
